UNITED STATES PATENT OFFICE

ELMER CLIFFORD CARLSON, OF MINNEAPOLIS, MINNESOTA

SHOPPING BAG

Application filed February 15, 1926. Serial No. 88,176.

My invention relates to improvements in bags and has for its object to provide a slightly shopping bag of commodious dimensions adapted to be readily converted into a 5 relatively small and compact handbag, which is neat and attractive in appearance.

A more specific object of the invention resides in providing a receptacle, open at its top, consisting of front and back body members, the front body member having a purse attached to its upper marginal portion, the back body member having a keeper flap similarly attached thereto, said bag being foldable transversely to bring the lower portion 15 thereof upon the upper portion, the folded structure thus formed being thereafter foldable on lines extending from top to bottom thereof to bring wing-like portions of said structure together edge to edge beneath the 20 flap for engagement therewith, whereby a pouch is left available between said body members and a second pouch is provided between the folded portions of said members.

A further object resides in cutting away 25 the upper corners of the body members so that said wing-like portions may fold freely below the seam of said flap and into position permitting said flap to lie flatly thereagainst.

With the foregoing and other objects in 30 view, which will appear in the following description, the invention resides in the novel combination and arrangement of parts and in the details of construction hereinafter described and claimed.

35 In the drawings illustrating my invention: Fig. 1 is a perspective view of my improved shopping bag illustrating the same in extended form.

Fig. 2 is a view similar to Fig. 1 illustrating the bag from one side thereof in folded form.

Fig. 3 is a view similar to Fig. 2 illustrating the bag from the reverse side.

Fig. 4 is a central, sectional view taken on 45 a line running from top to bottom of the folded bag structure, the scale being considerably enlarged over the remaining views.

The embodiment of my invention, illustrated in the drawings, comprises primarily 50 a receptacle A, which is constructed of a

single piece of coated fabric or other suitable material doubled up along a transverse line 11 to provide front and back body members 12 and 13. These members are sewed together (not shown) or otherwise secured 55 along their edges 14 and 15 so as to form an open ended container adapted to receive and hold parcels. On the body members 12 and 13 at the upper edges thereof are attached two loops 17 and 18 which may be constructed 60 of leather, webbing or the same material as the bag and which are stitched along said edges to form handles by means whereof the bag may be conveniently carried in either its extended or folded form. The upper corners 65 of the body members 12 and 13 are cut away to give the bag a pleasing appearance and at the same time to serve a purpose to be later described. The edges of the bag at the mouth thereof are neatly hemmed or bound 70 as indicated at 19 to strengthen the bag and add to its appearance.

To convert the bag into a handbag, the lower portion 20 of said bag is folded transversely along a line 21 so as to bring this portion of the bag upon the front of the upper portion 22 thereof. The fold 21 is situated below the middle of the bag a sufficient distance so that the bottom fold 11 of said bag falls considerably below the upper edge of 75 the front body member 12 as clearly shown in Fig. 3. The lapping top and bottom portions 20 and 21 of the bag are folded jointly along two folds 23 and 24 extending at right angles with respect to fold 21, wing-like 80 marginal portions of the folded structure, meeting edge to edge along the center of the bag at the back thereof as best shown in Fig. 2. This transforms the shopping bag into a handbag of greatly reduced dimensions and 85 forms two compartments or pouches 25 and 26 in which various articles may be placed when the bag is used in its folded form. The compartment 25 is enclosed by the two body members 12 and 13 and terminates at the 90 folds 21, 23 and 24, being a confined portion of the entire space within the receptacle A. The compartment 26 is enclosed between the folded portions of the front body member 13, the same terminating at the fields 21, 23 and 95 100

24. For illustrating the utility of this compartment a handkerchief 27 is shown in Fig. 3 as inserted within the same. The fold 21 as will become apparent forms a false bottom for both of these compartments so that articles may be placed therein and so kept without danger of loss.

The manner of holding the bag in folded form can best be comprehended from an inspection of Figs. 1, 2 and 4. Along the upper edge of the back body member 12, is attached by means of a seam 28, a keeper flap 29. This keeper flap is adapted to cover the meeting edges of the wing-like marginal portions of the folded bag structure. Upon this keeper flap are attached snap fastener members 30, which are adapted to co-operate with complementary snap fastener members 31 secured to the back body member near the lower corners thereof. When these fastener members are engaged, the keeper flap 29 ties together the folded wing-like marginal portions of the bag and prevents the sagging thereof, whereby all of the folded portions of the bag are prevented from unfolding, so that the compartments in the same may be utilized without danger of the bag coming apart. To hold keeper flap 29 in place when the bag is extended for use as a shopping bag, I provide two snap fastener members 32, which are secured to the back body member 12 beneath the snap fastener members 30. When these snap fastener members 30 and 32 are interlocked, flap 29 is caused to lie flat against the bag proper in inconspicuous position of disuse.

In conjunction with the compartments 25 and 26 for holding articles of merchandise, I employ a coin purse 33 shown in Fig. 3, which may be secured to the front body member 13 by stitching or in any other suitable manner. This purse may be constructed of the same material as the remainder of the bag and consists of a front 34 and back 35 terminating in a flap 36 which front and back may be stitched together at their edges and to the body member 13. The flap 36 is secured to the purse 33 by means of a snap fastener 37 in the usual manner.

50 In the use of the invention as a shopping bag the fastener members 30 are unloosened from the fastener members 31 and the folded portions of the bag unfolded and dropped. Prior to this, however, it becomes necessary 55 to remove articles from compartment 26 as this compartment disappears when the bag is unfolded. As to articles in compartment 25, the same may be left therein as they simply drop to the bottom of the receptacle 60 when the bag is unfolded. It will be noted that the position of the coin purse is the same whether the bag is extended or whether it is folded so that said purse is conveniently accessible at all times. The turning of the 65 wing-like marginal portions of the lapping

upper and lower portions 20 and 22 of the bag is readily accomplished due to the fact that the upper corner portions of the bag are cut down so that said portions fall well below the seam of flap 29. This will become 70 readily apparent from an inspection of Fig.

2. In folding up the bag, when it is desired to use it as a handbag, said bag is folded successively along the lines 21, 23 and 24 as explained, and the fastener members 30 on flap 29 engaged with fastener members 31 on body member 12. The portion 20 of bag A is preferably folded so that the bottom 11 of the folded bag falls somewhat below the upper edge thereof, which leaves 80 sufficient space for attaching the purse 33 to the body member 13 without interference with the folded up portion 20. With this arrangement articles may be readily placed in or removed from the compartment or 85 pouch 26 without catching on said purse.

The invention is particularly advantageous in that the entire bag may be made of the same material and does not require any special machinery for its manufacture. The 90 bag is handsome in appearance in both its extended and folded form and may be quickly changed to either form.

Changes in the specific form of my invention, as herein disclosed, may be made within 95 the scope of what is claimed without departing from the spirit of my invention.

Having described my invention, what I claim as new and desire to protect by Letters Patent is:

1. A shopping bag comprising front and back body members forming a receptacle open at its top, a flap secured to one of said body members along the upper edge thereof, the marginal portions of said back at the 105 open end thereof being cut away at either side of said flap, said bag being foldable transversely to bring the lower portion thereof upon the upper portion, both of said upper and lower portions being foldable jointly 110 along longitudinal lines to bring portions thereof together edge to edge upon the surface to which said flap is attached and beneath said flap, said cut-away marginal portions falling freely below the seam of said 115 flap.

2. A shopping bag comprising a receptacle, the lower portion thereof being foldable upon the upper portion, both of said lower and upper portions, in lapping relation, being foldable jointly along lines extending between the middle and the side edges of said bag to bring wing-like marginal portions of the folded structure upon the opposite side of said bag so as to provide a pouch between said upper and lower bag portions confined between said folds, a flap secured to said bag adapted to overlie the adjacent edges of said folded wing-like marginal portions, and co-operating fastener members secured to said 130

flap and to said wing-like portions of said bag for holding the bag folded, said pouch remaining open upon the attachment of said flap to said wing-like portions.

5 3. A shopping bag comprising front and back body members forming a receptacle open at its top, a purse secured to one of said body members at the upper part thereof, a flap secured to the other of said body members along the upper edge thereof opposite said purse, the marginal portions of said bag at the open end thereof being cut away at either side of said flap and purse, said bag being foldable transversely to bring the lower 15 portion thereof upon the upper portion with the lower edge of said bag falling beneath the lower edge of said purse, both of said lower and upper portions being foldable jointly along longitudinal lines to bring portions thereof together edge to edge on the opposite side of said bag and beneath said flap, said cut-away marginal portions falling freely below the seam of said flap, the folding of said bag portions providing a pouch between said upper and lower portions confined between said folds, and fastener members on said bag and flap for holding said folded portions in folded position.

4. A bag including a front and a back, a flap secured along its upper margin to the upper margin of the back medially thereof, the bottom portion of the bag being foldable upon the upper portion of the front of said bag, said folded structure being further foldable along two spaced lines to bring the marginal portions at the sides thereof upon the back of the bag and into position between said flap and said back, the upper edges of both front and back at either side of the flap 40 being lower than the junction between said flap and said back to cause the upper edges of said marginal portions to clear the junction between said flap and back, and means for fastening the flap to said marginal portions in the folded position thereof to tie said portions together and to support them against sagging.

5. A bag including a front and a back, a flap secured along its upper margin to the upper margin of the back, the bottom portion of the bag being foldable upon the upper portion of the front of said bag, said folded structure being further foldable along two spaced lines to bring the marginal portions at the sides thereof upon the back of the bag and into position between said flap and said back, and means for fastening the flap to said marginal portions in the folded position thereof to tie said portions together and to support them against sagging.

6. A bag including a front and back, a flap secured along its upper margin to the upper margin of the bag, the bottom portion of the bag being foldable upon the upper portion of the front of the bag, said folded struc-

ture being further foldable along two spaced lines to bring the marginal portions upon the back of the bag and into position between said flap and bag, fastening members secured on said back near the corners thereof, and complementary fastening members secured to said flap adapted to engage said first named fastening members, said flap serving to hold said folded structure in closed position and to prevent the sag of the folded portions of the bag.

7. A bag including a front and back, a flap secured along its upper margin to the upper margin of the bag, the bottom portion of the bag being foldable upon the upper portion of the front of the bag, said folded structure being further foldable upon the reverse side of the bag so as to leave the bottom edge of the bag free along the front of the bag to provide an open pouch and means formed on said flap and bag for holding the folded corner portions of said bag in fixed position relative to the bag to preserve the form of the pouch formed between the folded structure of said bag.

In testimony whereof, I have signed my name to this specification.

ELMER CLIFFORD CARLSON.
